UNITED STATES PATENT OFFICE.

JEAN KAPPELER, OF MELLINGEN, SWITZERLAND.

BRAIDING MACHINE.

1,330,323.

Specification of Letters Patent. Patented Feb. 10, 1920.

Application filed August 7, 1918. Serial No. 248,773.

To all whom it may concern:

Be it known that I, JEAN KAPPELER, a citizen of the Republic of Switzerland, and resident of Mellingen, Canton of Argovie, Switzerland, have invented new and useful Improvements in Braiding-Machines, of which the following is a full, clear, and exact specification.

The known braiding bobbins in braiding machines, which travel in a grooved guide-plate, have ordinarily at their lower spindle end a shuttle-like elongated sliding shoe, by means of which they are guided in the groove of the guide-plate. In this arrangement, owing to the fixed position and to the relatively great longitudinal extent of this sliding shoe, it frequently happens that in sharp curves of the guiding groove there occur considerable strains in the same which cause great friction and wear as well as a disagreeable noise.

The present invention obviates these drawbacks. According to the invention, the braiding bobbins of a braiding machine are provided at their lower spindle ends with at least one pair of short, independent sliding shoes, which are arranged one behind the other in the same longitudinal path and are each rotatable about an axis parallel to that of the bobbin, so that they are able to adapt themselves automatically in all the curved parts of the guide-way of the guide-plate to the corresponding curvature of the same. There results therefrom a smooth and easy traveling of the braiding bobbin with only a little friction and almost without noise.

Preferably the braiding bobbin has two such pairs of sliding shoes in parallel arrangement to each other and at such a relative distance from each other that the sliding shoes of the two pairs can be caused to slide along both sides of a guide-rib or rail, which insures a good and sure guidance of the bobbin without staggering, the bobbin being in some respect by its shoe pairs put in riding position over the guide-rail.

To allow of rotation of the sliding shoes, they may be mounted for example on rotary disks rotatably engaged in the spindle foot of the bobbin. These rotary disks may be provided with peripheric grooves and guided thereby in rolling contact on a fixed intermediate guide-pin carried by the spindle foot of the bobbin.

The accompanying drawing shows an embodiment of the present invention;

Figure 1 is a side elevation of the whole of a braiding bobbin with a vertical transverse section through a guide-plate of a braiding machine;

Fig. 2 is a detail vertical section through the foot part of the bobbin;

Fig. 3 is a view from below corresponding to Fig. 2;

Fig. 4 is a horizontal section on line A—B of Fig. 2;

Fig. 5 is a horizontal section on line C—D of Fig. 1.

The braiding bobbin or spindle as represented is provided at its lower spindle end with two pairs of short, independent shuttle-like sliding shoes *a*, *b* and *a'*, *b'*. The pair of shoes *a*, *b* is in parallel arrangement to the pair of shoes *a'*, *b'* as clearly shown by Fig. 3. The shoes of each pair are arranged one behind another in the same longitudinal path. In the use of the bobbin on a guide-plate *c*, one pair of shoes is engaged into a guiding groove *c'* and the other into a parallel guiding groove *c''* of the double-grooved guide-plate *c* (Figs. 1 and 5), whereby the relative distance between the pairs of shoes corresponds to the thickness of the guide-rib or rail *d* between the two grooves *c'*, *c''*, so that the two pairs of shoes are guided along both sides of the rib or rail *d*. In order to allow the sliding shoes to adapt themselves to the curvature of the guide-rail *d*, which is particularly necessary in sharp curves, so that the traveling of the bobbin can take place without strain and with the smallest friction possible, the forward sliding shoes *a*, *a'* and the rear sliding shoes *b*, *b'* are rotatable about an axis parallel to the spindle axis, the sliding shoes *a*, *a'* being mounted on a rotating disk *f*, those *b*, *b'* on a second rotating disk *f'*.

These disks *f*, *f'* are provided with a peripheric groove and guided by means of the same, in rolling contact, on a fixed intermediate guide-pin *g* held fast in the lower part of the bobbin spindle.

The drive of the bobbin may be effected in the usual manner by means of driving plates. The guidance of the bobbin, owing to the arrangement of the two pairs of shoes riding upon the guide-rail *d*, is the best possible and free from any staggering, while in consequence of their angular adjustability the sliding shoes move without any strain and noise along the sides of the guide-rail.

Obviously, the bobbin spindle can also be

provided with only a single pair of rotatable sliding shoes. In this case, which is important for the usual one-path guide-plates, the sliding shoes would tightly slide in the 5 guiding groove of the guide-plate.

What I claim is:

1. In braiding machines, the combination of a guide-plate having a curved guide-way and of braiding bobbins guided by the same 10 and provided at their lower end with a pair of short, independent sliding shoes, which are arranged one behind the other in the same longitudinal path and are rotatable each about an axis parallel to that of the bobbin, so that they can adapt themselves automatically in all the curved parts of the 15 guide-way to the corresponding curvature thereof.
2. In braiding machines, the combination 20 of a guide-plate having a curved guide-rail or rib and of braiding bobbins guided by the latter and provided at their lower end with two pairs of short, independent sliding shoes, which in each pair are arranged one 25 behind the other in the same longitudinal path and are rotatable each about an axis parallel to that of the bobbin, said two pairs of sliding shoes being placed at such a distance from each other that they are guided 30 along both sides of the said guide-rail or rib while being self-adjustable to the curvature thereof.
3. In braiding machines, the combination 35 of a guide-plate having a curved guide-way and of braiding bobbins guided by the same and provided at their lower end with a pair of short, independent sliding shoes, which are arranged one behind the other in the same longitudinal path and are carried by

rotatable disks mounted in the lower part of 40 the bobbin so as to be capable of angular displacement about an axis parallel to the bobbin axis, in view of their self-adjustability to the curvature of the guide-way.

4. In braiding machines, the combination 45 of a guide-plate having a curved guide-rail or rib and of braiding bobbins guided by the latter and provided at their lower end with two pairs of short, independent sliding shoes, which in each pair are arranged one behind 50 the other in the same longitudinal path and are rotatable each about an axis parallel to that of the bobbin, the forward shoes of the two pairs being carried by a rotatable disk and the rear shoes of the two pairs being 55 carried by another rotatable disk, whereby the said two disks are mounted in the lower part of the bobbin and are in rolling contact with a common intermediate guide-piece.

5. In braiding machines, the combination 60 of a guide-plate having a curved guide-way and of braiding bobbins guided by the same and provided at their lower end with a pair of short, independent sliding shoes, which are rotatable each about an axis parallel to 65 that of the bobbin, so that they can adapt themselves automatically in all the curved parts of the guide-way to the corresponding curvature thereof.

In witness whereof I have hereunto signed my name this 6th day of July, 1918, in the presence of two subscribing witnesses.

JEAN KAPPELER.
